UNITED STATES PATENT OFFICE.

SAMUEL G. HIBBEN, OF BLOOMFIELD, NEW JERSEY.

DESIGN FOR A LIGHTING-FIXTURE.

59,087.

Specification for Design. Patented Sept. 20, 1921.

Application filed January 27, 1921. Serial No. 440,510. Term of patent 3½ years.

To all whom it may concern:

Be it known that I, SAMUEL G. HIBBEN, a citizen of the United States, residing at Bloomfield, New Jersey, have invented a new, original, and ornamental Design for a Lighting-Fixture, of which the following is a specification, reference being had to the accompanying drawings, forming a part thereof.

The figure is a perspective view of a lighting fixture, showing my new design.

I claim:

Ornamental design for a lighting fixture, as shown.

SAMUEL G. HIBBEN.
